FIG. 1

FIG. 2

UNITED STATES PATENT AND TRADEMARK OFFICE
CERTIFICATE OF CORRECTION

PATENT NO. : Des. 465,636 S
DATED : November 19, 2002
INVENTOR(S) : Allen et al.

Page 1 of 1

It is certified that error appears in the above-identified patent and that said Letters Patent is hereby corrected as shown below:

Title page.

Item [56], U.S. PATENT DOCUMENTS, delete
“2,190,949 A * 2/1940 Plems ..... 426/621” and insert
-- 2,190,949 A 2/1940 Plews ..... 99/82, -- therefor.

OTHER PUBLICATIONS,

“Packaging Flat for smacks Cereal and Milk Bars” reference, delete “KelloGg’s” and insert -- Kellogg’s --, therefor; delete “smacks” and insert -- Smacks -- therefor; and delete “KelloGg’s” and insert -- Kellogg’s --, therefor.

“Calif raises the bar” reference, delete “Calif” and insert -- Clif --, therefor.

“Crunchy Nut (Australia) Corn Flake Cereal Bars” reference, insert -- Packaging Label for -- before “Crunchy”.

“Nutri Grain Twists” reference, insert -- Packaging Label for -- before “Nutri”.

“Packaging Label for Boost” reference, delete “pages” and insert -- page --, therefor.

“Packaging Label for Clif Bar” reference, delete “SportsNaturals” and insert -- Sports Naturals --, therefor.

“Packaging Label for Clif Kicks Bar” reference, delete “Kali’s SportsNaturals” and insert -- Kali’s Sports Naturals --, therefor.

“Packing Label for Whole Grain Bars” reference, delete “Packing” and insert -- Packaging --, therefor.

“Packing Label for New Yorker Breakfast Bar” reference, delete “Packing” and insert -- Packaging --, therefor.

“Packing Label for Oreo Granola Bars” reference, delete “Packing” and insert -- Packaging --, therefor.

“Packaging Label for Snack well’s Cereal Bars” reference, delete “Snack well’s” and insert -- Snackwell’s --, therefor.

“Power Bark for Find” reference, insert -- Packaging Label for -- before “Power”.

“Power Bark for Find.” reference, delete “Find.” and insert -- Fido --, therefor.

Signed and Sealed this

Eleventh Day of March, 2003

JAMES E. ROGAN
Director of the United States Patent and Trademark Office
